UNITED STATES PATENT OFFICE

RALPH D. FITZGERALD, OF NEW KENSINGTON, PENNSYLVANIA

CLOSURE STRIP

Application filed March 16, 1931. Serial No. 522,855.

My invention relates to a closure strip, and while primarily intended for use in connection with doors, windows, shutters, and the like, for rendering such closure elements noiseless in operation, weather and dust proof, it will be obvious that the device may be employed with other types of structures, and for any other purposes wherein it is found to be applicable.

Important objects of the invention are to provide a closure strip of the character described, which may be readily installed to any type of closure element already erected as well as form a component part of a new structure, which embodies a replaceable and resilient cushioning member, which is simple in its construction and arrangement, durable and efficient in its use, compact, attractive in appearance, and comparatively inexpensive to manufacture, install and maintain.

With the foregoing and other objects in view which will appear as the description proceeds, the invention consists of the combination and arrangement of parts and in the details of construction hereinafter described and claimed, it being understood that changes in the precise embodiment of the invention herein disclosed can be made within the scope of the claims hereunto appended without departing from the spirit of the invention.

In the drawing wherein like numerals of reference designate corresponding parts throughout the several views:

Figure 1 is a transverse cross sectional view of my improved closure strip and of associated closure elements, the latter being broken away.

Figures 2 and 3 are, respectively, front and perspective views of the device.

Figures 4 and 5 are, respectively, inner edge and end views of a corner member embodying the present invention.

Figure 6 is a transverse cross sectional view of the device embodying a modified form of cushioning member, and illustrating its adaptation with metallic closure elements.

Referring in detail to Figure 1 of the drawing, the invention is therein illustrated as embodied in a wooden door structure of the usual construction. The door structure in-

cludes a door 1 and one of the upright members 2 of the associated door frame.

My improved closure strip comprises an elongated body portion 3, and while preferably constructed from metal, it will be apparent that the same may be formed from any other suitable material. The body portion 3 is formed with a channel 4 extending longitudinally along the inner edge and throughout the entire length of the former. The channel 4 is open at its inner side, as at 5, is mainly disposed at the front side of the body portion 3, and is somewhat more than semi-cylindrical in transverse cross section.

The front side of the body portion 3 is provided with a pair of reinforcing ribs, respectively indicated at 6 and 7. The rib 6 is comparatively narrow and disposed on the outer edge margin of the body portion 3. The rib 7 is relatively wide and disposed contiguous to the channel 4. The ribs 6 and 7 are preferably of uniform thicknesses, and in conjunction with the channel 4, establish the required rigidity of the body portion 3.

The body portion 3, when employed in a door structure, as illustrated in the drawing, extends vertically against each of the upright members 2 and horizontally against the head member of the door frame, and replaces the ordinary wood joint strip now commonly used in wood door structures for limiting the closing movement of the associated door, and for closing the joint around the latter in the door frame.

The body portion 3 is secured in position to the door frame by a plurality of screws 8, which are engaged in spaced countersunk apertures 9 provided therefor in the wide rib 7 of the body portion.

The back side 10 of the body portion 3, is flat and extends on an even plane throughout its area, with the exception of a sharp seating ridge 11, which is disposed adjacent to the channel 4 and extends longitudinally throughout the length of the body portion 3. When the body portion 3 is secured to respective door frame members by the screws 8, the sharp seating ridge 11 will be forced into said door frame members, thereby providing a juncture between the latter and the body por-

tion 3 that is impervious to the passage of air or any extraneous matter.

Corner members 12, having a transverse cross sectional contour identical to the body portion 3 and likewise secured to the upper corners of the door frame by screws, are provided for establishing continuity between the upper ends of the body portions 3 secured to the upright members of the door frame and 10 respective ends of the body portion 3 secured to the head member of the door frame.

A tubular, cylindrical cushioning member 13, preferably constructed from soft rubber, is mounted in the channel 4, and extends 15 throughout the lengths of the body portion units and corner members 12 employed in the door structure. The cushioning member 13, being tubular and constructed from soft rubber, is susceptible of sufficient distortion to 20 allow the same to be forced into and from the channel 4 through the opening 5 at the inner side of the latter.

The inner side of the cushioning member 13 projects through the opening 5 in the 25 channel 4, as clearly shown in Figure 1. This projecting portion of the cushioning member 13 provides the abutment engaging the side and top edge margins of the door 1 when the latter is in the closed position.

30 As the cushioning member 13 is inherently resilient, and the channel 4 has somewhat more than a semi-cylindrical configuration, the former, when forced into the channel 4, will securely grip the latter and maintain 35 itself in position until forcibly removed for replacement or for any other purpose required.

An important advantage in the use of my 40 improved closure strip, is that it will render the closing of doors absolutely noiseless, whereby its installation, to all doors of homes, public buildings, hospitals or other institutions, is invaluable in obviating the incessant slamming of door so annoying to the occupants of the buildings. Further, owing to 45 the flexibility of the tubular cushioning member 13, the associated door will closely engage same, and thereby provide a closure joint that is dust, weather, and almost sound proof.

50 Figure 6 illustrates the adaptation of the present invention to a metal door structure, which includes the door 14 and the frame member 15. In securing the body portion 3 to the metal frame member 15, a filling strip 55 16, constructed from rubber or any other suitable material, is interposed between the back of the body portion 3 and the frame member 15 to compensate for the seating ridge 11, which of course, cannot be forced into the metal frame member 15. The filling strip 16, however, provides an effective weather proof 60 joint between the body portion 3 and the metal frame member 15.

A modified form of the cushioning member 65 17 is shown in the embodiment of the inven-

tion illustrated in Figure 6. The cushioning member 17 differs from the preferred form of cushioning member 13, herein before described, in that the cushioning member 17 is solid and not tubular. The cushioning member 17, being constructed from soft rubber, 70 may be forced into and from the channel 4 in the manner described relatively to the preferred form, and is but slightly less efficient for the purposes intended than the tubular cushioning member 13 embodied in the preferred form of the device. 75

While the configuration of the body portion 80 3 herein illustrated and described is thought to be the best embodiment thereof, it is evident that the contour of the body portion may be widely varied to best meet conditions found in practice, without departing from the spirit of the invention.

The present invention provides a most efficient device of its kind, which can be economically manufactured and installed in any type 85 of closure element to render the latter sound, dust, and weather proof.

What I claim is:—

1. In combination, a closure strip of the 90 character described, comprising an elongated body portion constructed from metal and being provided with a channel extending along one side edge thereof, a cylindrical cushioning element being removably mounted in said channel and projecting from one side of the latter throughout its length, and a seating ridge formed on the back side of said body portion and extending throughout the length 95 of the latter. 100

2. In combination, a closure strip of the 105 character described, comprising a elongated body portion constructed from metal and being provided with a channel extending along one side edge thereof, a cylindrical tubular cushioning element being removably mounted in said channel and projecting from one side of the latter throughout its length, a seating ridge formed on the back side of said body portion and extending throughout the length 110 of the latter, the front side of said body portion being formed to provide a pair of reenforcing ribs. 110

In testimony whereof I affix my signature. 115
RALPH D. FITZGERALD.
